US0D1028627S

(12) **United States Design Patent** (10) **Patent No.:** **US D1,028,627 S**
(45) **Date of Patent:** **** May 28, 2024**

(54) **DRINKING VESSEL**

(71) Applicant: **SPEARMARK HOLDINGS LIMITED**, London (GB)

(72) Inventor: **Terence Anthony Bloom**, London (GB)

(73) Assignee: **SPEARMARK HOLDINGS LIMITED**, London (GB)

(**) Term: **15 Years**

(21) Appl. No.: **29/847,311**

(22) Filed: **Jul. 22, 2022**

(51) LOC (14) Cl. **07-01**

(52) U.S. Cl.

USPC **D7/536**

(58) **Field of Classification Search**

(57) **CLAIM**

The ornamental design for a drinking vessel, as shown and described.

DESCRIPTION

FIG. 1 is a perspective view of a drinking vessel showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
